AMMUNITION

Leigh Forstner Birkeland, Luke Field, Ariz.

Application January 11, 1944, Serial No. 517,801

3 Claims. (Cl. 102—50)

(Granted under the act of March 3, 1883, as
amended April 30, 1928; 370 O. G. 757)

1

The invention described herein may be manufactured and used by or for the Government for governmental purposes without the payment to me of any royalty thereon.

The invention relates to ammunition and particularly to a projectile having characteristics adapting it to use with conventional weapons and loading practice to attain higher velocities with consequent flattening of the trajectory over distances sufficient for effective combat.

While such attainments have importance in all calibers for many situations, they are particularly important in small arms, and have superior value in aerial combat.

The invention in its present embodiment has for an important object to present a form adapted to use in current gun forms, and utilizing largely present practice in ammunition manufacture and preparation for use; shipping and handling from factory to gun, and enabling use of familiar ammunition belt assembly, and breech and firing mechanism of conventional forms. That is to say, while the projectile is longer, its exposed part in a round is approximately conventional in size and shape. In these respects the invention is specially useful in infantry small arms as well as in weapons for aerial combat. It is well adapted to use in weapons such as the 50 caliber or larger aircraft machine gun, and is thought of value in aircraft cannon.

For aerial combat and in firing small arms generally, the low quadrant angle of departure, and generally flat trajectory enable point blank firing at considerable ranges, and considering the element of lead of the target as included. The lead required however is reduced, and accuracy correspondingly enhanced.

Incident to the attainment of the foregoing objects it is a purpose of the invention to effect a substantial reduction in the factors of energy expended in the burning of the powder charge, by which the projectile is propelled, other than that factor involved in translation of the projectile and in fact to eliminate at least one of, if not the most important two, viz: energy of rotation of the projectile, and the energy consumed in engraving of the rotating band by the rifling, and the additional components of friction involved between the lands and the engraved parts. In addition I have materially reduced relatively those factors comprising the energy of translation of the gun and energy lost as heat to the gun.

Relative to a given movement of the projectile, however, I have not only converted the savings

2

in other factors to a greater factor of energy of translation of the projectile, but have further greatly increased this force, by a coordinated modification of the propelling powder, without increasing the stresses developed in the barrel of the gun.

It is a specific aim of the invention to obviate need for rifling in the gun and to enable use of a smooth bore, thereby reducing materially the cost of the weapon and avoiding expense for new tools in production of the arm; and at the same time eliminating a large element of friction and the factor of torque energy heretofore expended on the projectile with the sacrifice of velocity.

15 To compensate for this elimination of rotation in the gun, it is a purpose to so construct the projectile that it will maintain stability of flight and a good approximation of alignment of its axis with the trajectory. In effecting stabilization, I have formed a projectile of greater length for a given mass, with its center of gravity further forward, and it is an important attainment of the invention that this projectile and a standard cartridge case are embodied so as to be readily assembled in the conventional clips, bandoliers, magazines, and machine gun belts, and to function in the same manner as prior ammunition in breech and firing mechanisms.

20 A further purpose is to reduce head resistance of air to the progress of the projectile and particularly to eliminate or reduce the zone of air density at the nose of the projectile by which it tends to be yawed, and to reduce other elements of drag both in flight and in the gun.

25 It is also a purpose to reduce the weight of the projectile in order to gain still further velocity, and at the same time enable the benefit of increased velocity to be maintained over a satisfactory range.

30 A further purpose is to enable a further gain of velocity by the use of a more rapidly burning propelling powder charge, and, by reason of the greater acceleration of the projectile due to the modification of factors of energy expended, to produce a conventional pressure curve, of barrel length and pressure with the new powder, notwithstanding its high burning rate. This enables the use of conventional proportions in the barrel, and further avoids expense in manufacturing costs.

35 Another object is to enable the use of a tubular projectile, with novel functions in the firing and flight operations, and otherwise. At the same time that the foregoing objects and advantages

are attained, it is a still further object to utilize therein the standard aircraft machine gun currently used so that it will remain, both in principle and operation identical with the standard type.

It is an important desideratum in this invention to provide for the communication of the propulsive force of the burned charge over a maximum cross sectional area of projectile, so as to most effectively utilize the available accelerative force, limited only by the caliber of the gun, yet during propulsion to substantially reduce the presented area and consequent head resistance and drag as compared to conventional projectiles having an equal effective cross section on firing. That is to say, the flight caliber of the projectile is substantially less than its initial or loading caliber.

Likewise it is sought to lessen the degree of vacuity at the tail of the projectile in flight.

Additional objects, advantages and features of invention reside in the construction arrangement and combination of parts involved in the embodiment of the invention and its practice otherwise as will be understood from the following description and accompanying drawings wherein

Figure 1 is a view of a round of ammunition embodying my invention partly in elevation, the projectile and cartridge case being in longitudinal section;

Figure 2 is a similar view of a modification using a solid projectile.

Figure 3 is a rear view of the projectile.

Figure 4 is an enlarged fragmentary longitudinal section of the base of the projectile head and tail.

Figure 5 is a schematic sectional view of a tapered bore gun and a representation of my projectile at successive positions therein on firing.

I am aware that the principles of rocket projectiles have been incorporated in ammunition heretofore, but my invention is distinguished from these prior efforts in several important respects, as will appear.

There is illustrated a round of ammunition comprising a cartridge case 10, which may be produced as usual in a conventional form as heretofore and in a size proportionate to the caliber and construction of the gun in which it is to be used. It may be loaded and primed conventionally (the primer not being shown), except that the propelling charge 11 may be of a faster burning quality than usual for a cartridge of a given size and conventional projectile. While I have contemplated using my invention in guns constructed as those now used in the smaller calibers, except for omission of rifling, still, my invention is specially advantageous for use in smooth tapered bore guns, and my cartridge is suggestively shown tapered, although it may conform to other standard shapes heretofore used.

Due to the fact that no change in known gun structure is contemplated, excluding the omission of rifling, I have not illustrated the gun in detail.

The case 10 is formed with the usual forward reduced neck 12, heretofore adapted to enter into the bore of the gun behind the rifling and the rearward enlarged chamber-fitting part 13, a joining conical shoulder part 14 intervening.

The projectile may be solid as in Figure 2, and of a weight corresponding to that of the conventional bullets heretofore used in weapons of the same caliber, but in Figure 1, I have shown the projectile 15 much lighter by reason of imparting thereto a tubular form, in order to attain all of

the advantages and objects heretofore stated, as well as others which will be manifest.

In Figure 1 the projectile consists of a bullet head 16, the length of which corresponds to that of the conventional bullet, but instead of having a pointed nose, has a broadened nose 17 of annular form terminating in a plane at right angles to the axis of the projectile, the ogival curve 18 terminating forwardly immediately at this annular nose, and having a radius of approximately ten calibers, as shown, although this may be varied to accordance with current practice, or otherwise for special performance characteristics found practicable with my invention. A coaxial cylindrical bore or passage 19 is formed longitudinally entirely through the head 16, the diameter of which is but slightly less than the maximum external diameter of the nose 17, depending on how sharp an edge 20 it is desired to form on the annular termination of the nose. The diameter of the passage may be determined also in accordance with formulae based on desired flight characteristics including mass deceleration and avoidance of yawing. It is thought practicable in some aspects to remove material approaching seventy percent of the caliber in forming the passage 19. As illustrated, the proportionate measurement in relation to the caliber and length of the head is not intended as estimated or arbitrary, and will be largely affected by the most practical approximation of an ideal curve of deceleration of flight in the desired effective range of the projectile wherein the objects first set forth—or the more essential ones—are approximated.

The body or head terminates rearwardly at and with an annular thick interior base shoulder 21, in the present instance finished in a transverse plane, midway of the length of the reduced part 12 of the cartridge case 10, an integral thickened cylindrical rear wall 22 being continued rearwardly from the shoulder 21, the outerface of which is flush with the adjacent external face of the head 16. It extends as far as the junction of the neck and conical parts 12 and 14.

From the thick wall part 22, the material of the head is continued rearwardly with the same internal diameter, but slightly relieved on its external face, as at 23, forming a cylinder, or tubular tail 24 the length of which in this instance is sufficient to project into the cartridge case half the length of the latter, terminating in a plane normal to the axis of the projectile. The wall of the tail from the part 22 is of uniform thickness as shown but may be diminished in thickness toward its extremity, dependent on the refractory quality of the material therein, such tapering, if any, is preferably effected by diminishing the material at the inner side but maintaining a uniform external diameter.

A shoulder 25 defines the forward limit or boundary of the relieved part 23, but its radial altitude may be much less than shown, and it is believed that the difference may in effect be produced by the electrodeposition or other application of a face coating 26 (Figure 4) of a metal of low friction characteristics in engaging the face of a smooth-bore barrel, such as copper, tin, or other suitable metal or alloy. In the event that the projectile is used in a materially tapered bore, the relative thickness and form of the outer metal may be appropriately varied, if desired.

The body 15 and rearward extensions 22-24 may be formed of steel or other approved hard

tough metal for airplane use, but the major part of the head may be of some other metal, in accordance with approved practices, jacketed with steel or other metal; the jacket material preferably continued rearwardly to form the tail 24. The material of the head may also be specially adapted to progressive caliber reduction in the gun, as will be described.

The mouth of the cartridge case is set into the peripheral cannelure of the body 15 as customary heretofore, and indicated at 27.

Set separably against the shoulder 21, within the rear wall 22, there is a pseudo obturator, cap or stopper 28 without expansive quality, however, and intended to remain loosely set against the shoulder 21 but pressed tightly thereagainst by the expanding gases in the cartridge and barrel during propulsion of the projectile. The inner part 29 of this cap is semispherical or arched to withstand pressures within the cartridge case, and is of less diameter than the interior of the wall 22, so as to afford a material clearance therearound, while at the outer side of the stopper a boss 30 is integrally formed thereon, loosely fitted in the end of the passage 19. This stopper may be formed of a suitable metal, or may be made of a combustible or otherwise expendable material. In the first instance it will be cleared rearwardly from the projectile soon after leaving the gun, and in the second instance it may burn in part while in the gun and its combustion completed soon after. In one case the cap will be bodily expelled rearwardly by air rushing through the passage 19, or, in the other case, the remnants similarly expelled. In each instance, the cap functions as a transient closure device. The intermediate exterior portion 31 of the body of the projectile may be termed the bourrelet but, contrary to conventional practice, is of a diameter corresponding to that of the bore of a rifled gun at the bottoms of the grooves of the rifling instead of the lesser diameter involved at the tops of the lands. Also, contrary to conventional practice no clearance is contemplated between the bourrelet and the smoothbore, although if desired there may be a slight relief or modification of diameter at parts of the periphery of the head 16 to lessen the amount of material to be displaced in the entry and movement of the projectile through the barrel. This would involve such slight differences in conventional barrel forms that they may be produced by varying the amount of material applied or deposited on the exterior of the head or body of the projectile, at different parts.

In the case of a steel body 15 it may be found desirable to so proportion the applied material that displacement of material in the barrel will occur entirely in the applied material, avoiding higher stresses on the barrel which might develop if the steel body should require restriction to pass.

Operation

In the use of my invention as described, a gun having been provided with a smooth bore (which would enable a simple and economical renewal of life of a worn rifled tube), my ammunition prepared as described may be introduced or fed to the breech mechanism conventionally and fired as usual. Upon detonation, the powder having the new characteristics described and filling the cartridge including the space within and surrounding the hollow tail, burns quickly, the projectile moving forward and a small displacement

of the applied low friction material 26 occurring as the projectile enters the barrel. Thereafter the projectile moves with negligible impedance through the barrel with the heightened acceleration heretofore indicated.

In the burning of the powder contained in the tail portion, any expansive forces tending to enlarge the diameter of the tail is opposed and pressures equalized, by propagation of ignition in the space between the tail and wall of the cartridge case, and by translative movement of gases from the larger body of explosive rearwardly of the tail. The tail thus retains its cylindrical form and size as it moves from the cartridge. Incident to the passage of the projectile through a conventional shape of barrel having but slight if any taper, there will remain a clearance between the tail and wall of the bore by which the sustained pressures are equalized within and without the tail; so that no frictional engagement between the tail and barrel occurs.

Upon leaving the gun, after the pressure of propelling gases has diminished sufficiently, the air compressed into the passage 19, by its pressure and inertia and that progressively penetrated, will press the cap 28 rearwardly from the projectile, due to the greater mass of the projectile and the relatively greater area of the cap exposed to the air from the passage 19.

Should a cap 28 of combustible or otherwise expendable material be used its greater central thickness by reason of its semispherical rear face will delay combustion or collapse sufficiently for it to transmit the propulsive forces adequately until after the projectile leaves the barrel, after which particles remaining will be ejected rearwardly from the projectile as in the case of the metal or non-combustible caps.

As soon as the cap 28 is cleared, air passes through the passage 19 in substantial quantity, due in part to a compression thereof immediately at the nose of the projectile as well as to relative translative movement of the projectile and inertia of the air. This largely relieves the vacuous condition which tends to develop immediately behind the projectile, and in conventional projectiles becomes a material factor of deceleration. In addition, the head resistance and impedance is diminished, and also the small area of dense air formed in advance of the nose of ordinary projectiles is relieved, so that yawing forces incident thereto are largely, if not entirely eliminated. In the further flight of the projectile the center of gravity being located nearer the nose than the extremity of the tail, any tendencies of the projectile to yaw will be corrected by resultants of air forces acting on the tail, and the axis of the projectile will be maintained in a close approximation of alinement with the direction of flight, that is, the trajectory.

In Figure 2 I have shown a modification of the projectile in which, to gain greater mass in the projectile corresponding to that of a conventional projectile of the same caliber, I have omitted the axial passage in the projectile and have made the head or bullet element 32 solid, having conventional ogival surfaces and sharp nose 33, the remainder of the elements of the projectile being the same as in the first described form. The base face 34 of the bullet head is planiform and located somewhat further to the rear than the shoulder 21, while the rearward wall 22, corresponding to the one 22 before described, is of similar thickness, though shorter, since it stops at the conical part 14 of the case 10. The tail

24' is of the same shape diameter and length as that first described with a corresponding relieved outer surface. I have contemplated a further method of producing a reduction of head resistance in the projectile after obtaining the initial advantage of exposing a much larger transverse area to the propulsive forces of the barrel powder charge, and in Figure 5, I have shown schematically an exemplification of the use of my projectile in a suitable structural quality in a pronouncedly tapered gun bore.

In this instance a formal representation of a gun barrel or tube **35** is shown, the length of which is shortened for the purpose of illustration, although it may be of the same or a different relative length. The bore **36** is smooth and circular in cross section and is progressively reduced in diameter from the chamber **37** to the muzzle. The total reduction in diameter of the bore is proportionate to a predetermined fraction of the inner diameter of the passage **19** in the head **15**.

The material of the projectile is in this instance preferably readily compressible under forward progression in the bore with a moderate expenditure of energy of propulsion to overcome the additional friction and the internal resistance of the material of the projectile to such deformation. The projectile may otherwise be of the same form as before described (except that the ogival curve may be of materially shortened radius) and with the same elements as described in reference to Figure 1 herein. The stopper cap **38** if non-combustible should not exceed in diameter the minimum interior diameter of the tail after constriction and at its forward side is preferably conical, with low altitude of its conical elements.

In the use of the modified construction, a slower burning charge may be found more desirable than that used in the bore of conventional proportions, as may be determined by experiment and calculations familiar in interior ballistics.

Upon firing a round according with the modification last described, the equalization of pressures occurs as first described, within and without the tail, but in the event that the smaller diameter of the bore is less than that of the tail the latter will finally be engaged and compressed to the smaller diameter.

As the projectile progresses from the chamber position **a**, Figure 5, forwardly, it is compressed to a smaller diameter as at **b**, the passage **19** being correspondingly narrowed, until, when the projectile leaves the gun, the passage is quite small. If not closed, it may still function in flight to relieve the air density at the nose of the bullet, and also in part lessen the vacuity at the tail.

The whole projectile having passed from the gun it will have a cylindrical form in the reduced diameter, substantially as at **c**, Figure 5, and if the ogival curve has been sufficiently shortened the nose will also be considerably reduced. There may be a slight flaring of the forward part of the passage **19** due to lack of compressive action at the very tip of the nose.

In the movement of the tail portion through the barrel, by the selection of appropriate material, and due to the rapid heating of the entire cross section of the wall of the tail as well as the fact that finally practically all pressure acting on the tail will be from within, it will be firmly pressed against the wall surfaces of the bore as at **b**, Figure 5, and kept in a symmetrical circular contour while being reformed to the

smaller size. The projectile will be relatively more elongated in relation to its transverse dimension, if not actually elongated, and will thus approach more an ideal shape in relation to mass for sustained flight at high velocity. By the use of the stopper with conical face against the shoulder **21**, as the projectile becomes reduced in diameter the edges of the shoulder slide on the conical surface of the stopper, pressing it rearwardly and having it free at all times to be pushed rearwardly by air pressure acting through the passage **19** against lesser pressure at the rear.

While I have disclosed my invention with particularity in the best forms known to me, it will nevertheless be understood that these are purely exemplary and that modifications in the construction, arrangement, and combination of parts, substitution of materials and substitution of equivalents mechanically and otherwise, may be made without departing from the spirit of the invention, except as it may be more particularly limited in the appended claims wherein I claim:

1. A projectile consisting of a full caliber head portion having therein the major component of mass of the projectile and adapted for propulsion through a gun barrel and the like, said head having a longitudinal passage open entirely therethrough, a closure for the rear end of the passage freely displaceable rearwardly, and a tubular tail formed integrally on the projectile and being of less caliber measurement than the projectile but larger interior diameter than said passage, for free movement of the closure therethrough.

2. A round of ammunition comprising a conventional cartridge case having forward neck portion and a rear chamber portion, a projectile consisting of a full caliber head portion approximating standard length having therein the major component of mass of the projectile and having an integral thin walled cylindrical tubular tail of less diameter, the projectile head being set in the neck of the case and extended forwardly therefrom conventionally, said tail extending

30 concentrically into the chamber portion of the case, an axial air passage of less diameter than the tail being formed through the head, a charge of propellant in the case and within and around said tail and a loose expendable closure member of less diameter than the interior diameter of the tail arranged in the tail and set against the head at the end of the passage.

3. The structure of claim 2 in which said closure is of combustible material.

LEIGH FORSTNER BIRKELAND.
